UNITED STATES PATENT OFFICE.

HENRY RINK, OF PERHAM, MINNESOTA

POTATO PICKING AND SORTING MACHINE.

1,321,851.

Specification of Letters Patent. Patented Nov. 18, 1919.

Application filed May 9, 1918. Serial No. 233,493.

To all whom it may concern:

Be it known that I, HENRY RINK, a citizen of the United States, residing at Perham, in the county of Ottertail and State of 5 Minnesota, have invented certain new and useful improvements in Potato Picking and Sorting Machines, of which the following is a specification.

This invention relates to harvesting machines, more particularly that type employed for gathering fruit or vegetables which lie on the ground.

The primary object of the invention is to pick up articles, such as potatoes, vibrate 10 them rather roughly so that the dirt will be shaken off of them and the tops pulled off, and deliver them to a shaking screen whereby they are graded, the smaller ones dropping through the screen and being delivered to one side and the larger ones dropping off the screen and being delivered at 20 another point.

In carrying out this object, I make use of various instrumentalities, some of which are 25 old, but especially I employ a peculiar form of carrier which transports the articles along a series of longitudinal spaced fingers through which the dirt falls during the movement of the articles.

30 Details of the preferred construction of my invention are set forth in the following specification and claims, reference being made to the drawings herewith and in which:—

35 Figure 1 is a right side elevation of this machine,

Fig. 2 a central longitudinal sectional view,

40 Fig. 3 a perspective view of the vibrating carrier, and

Fig. 4 a perspective view of the main carrier,

45 Fig. 5 a perspective detail of a group of the so-called fingers such as overlie the carriers, excepting that these are mounted on a cross head of their own.

Long horizontal side bars 1 are connected at their front by a nose 2 in which is mounted the king bolt 3 of a yoke supporting the front axle and pair of wheels; and I may say at this point that the propelling mechanism for this machine may be any that will answer, such as power applied to the main axle or draft applied to the front 55 axle. The main axle 4 is connected by gearing 5 with the power shaft 6, and this

shaft and most of the elements hereinafter described are journaled in suitable bearings carried by a superstructure or framework 7. These details are not necessary to amplify. A running board 8 may be provided for one operator, and a seat 9 for the driver. The latter will drive the horses if horse power is employed, or will manipulate the levers if the machine is 60 driven by its own motive power, but the present specification is confined entirely to the mechanism for gathering and grading the articles, and the latter will be called 65 potatoes. Let us assume that the potatoes 70 have been dug and lie on the surface of the ground which surface is not necessarily even, and besides its ridges and gulleys it may have stones, while the potatoes will 75 certainly be very dirty and many of them have some of their tops yet attached. Instead of picking up these potatoes manually, I propose to gather them mechanically, and while gathering them I propose to 80 grade them into large size and small size, and perhaps deposit them in sacks or other receptacles.

There are two spaced points 10 which travel on or near or perhaps run through the ground, and between them a fixed blade 11 85 acting in the nature of a shovel to scrape up the potatoes, although of course it will gather up considerable dirt and such stalks as are attached to the tubers themselves. Immediately the gathered articles fall onto 90 a short carrier 12 with which the picker is provided. Referring now to Fig. 2, it will be seen that this carrier leads upward to a point where it overlies the main carrier 13 the latter being mounted in a frame 14 of 95 its own and to which the frame 15 of the small carrier is pivoted at the point 16. The front end of the main carrier and therefore the rear end of the small carrier may be adjusted vertically by a rod 17 connected with a hand lever 18 standing within reach of the driver.

I may here say that the main carrier (see Fig. 4) has a lower roller made up of sections 20 mounted loosely on a shaft 21, and 105 an upper roller 22 made in one piece mounted rigidly on the power shaft 6, and around these rollers travel chains 23 carrying cross strips 24—thus producing a transversely slatted structure which is quite 110 serviceable for gathering potatoes. A series of long fingers 25 have eyes 26 at their

front ends loosely embracing the shaft 21 between the roller sections 20 and their bodies stand between the chains 23 and underlie the strips 24, their remote ends resting as at 26' on the roller 22. Thus is made up a longitudinally slatted structure over which the strips slide as the upper stretch of the chain moves upward as usual, and accordingly it will be seen that the stationary portion of this structure is longitudinal whereas the traveling portion is transverse with the exception of the chains 23 which preferably move just inside the side bars of the frame 14. I have thus given a detailed description of the carrier, which is referred to again below.

Within the framework is disposed what I call the vibrating carrier as best seen in Fig. 3. Its frame 34 is suitably mounted at its front end on a shaft 33 standing some distance in rear of and below the main shaft 6 and carrying roller sections 30, and in the other end of the same is mounted a shaft 36 carrying a roller 32. Here also fingers 35 are employed, much like those numbered 25 in Fig. 4 and just described. Here also there are a pair of chains and cross strips moving to the rear on the upper stretch. But by preference I here employ another set of fingers 37 (see Fig. 5) mounted on a cross head 38, which cross head is pivotally supported within the framework 7 as best seen in Fig. 2. The result in this case is that the strips are moved longitudinally within the frame 34 over the lower set of fingers 35, while the upper set of fingers 37 overlie the strips, and therefore there is a double grating produced which I find extremely useful where the potatoes have many tops, or if other vines or weeds are gathered by the machine. The fingers 35 may be spaced to such an extent that the tubers hang through them and are struck by the strips in the lower stretch while the tops slide along these fingers and the resistance set up causes the potatoes to be separated from their vines and drop through the structure, while the tops pass off at the rear and are delivered back onto the ground. Meanwhile vibrating motion is given to the entire carrier by any appropriate means. I have shown upstanding ears 40 on the frame 34 having pins 41, and cams 42 rotated from an appropriate source strike these pins at intervals while springs 43 draw the entire frame back to its normal position after the cams have passed. This is a well known means for vibrating grain containing carriers or screens, and no novelty for the detail thereof is claimed; nevertheless I find this type of vibrator efficient although I might employ another.

Beneath this carrier is located what I call the lower grate 45, which is inclined down-

ward and to the left end delivers into a collecting trough 46. The latter contains a carrier 47 (see Fig. 2) by which all the potatoes are delivered to a second elevator broadly indicated by the numeral 48, and at the upper end of this is an inwardly extending spout 49.

Rollers 50 and 51 stand at a rearward incline beneath said spout and between baffle plates 52, one roller being driven by power from a suitable source and the other having its bearings pressed by springs 53 toward the first roller with the proper tension. All the potatoes thus far gathered are delivered by the spout to the rollers, and these tear from the tubers such stalks and roots as may yet be attached to them, while the rearward incline of the rollers themselves is sufficient to deliver the potatoes onto the next element which is the grader. The drawings show fully but thus far I have not described, the power mechanism for driving the various elements. This may well consist of sprockets and chains connected with the power shaft 6 so that the rotation of the main wheels, through the gearing 5, is utilized to drive the elements of the structure; and if the machine is driven by a motor mounted on its framework somewhere, the motor will doubtless be connected with said main wheels in a manner not necessary to amplify.

The grader 60 is here shown in the form of a shaking screen. It is mounted within a frame 61 which is hung on links 62 and the frame has a pin 63 knocked by a cam or crank 64 in each rotation of the shaft 65, much as shaking screens are often vibrated. I do not wish to be limited to this particular form, as any other which will answer the purpose may be equally effective. The mesh of the screen within the grader will determine the size of the potatoes sorted out, and this of course may be varied according to the wishes of the user. In any event, those sufficiently small will pass through the screen, and all others will pass over it. The larger potatoes will drop into the hopper 66 beneath the rear and lower end of the grader, and may be delivered through either of its spouts 67 and 68 according to which way the switch plate 69 is set. The smaller potatoes falling through the grader drop onto the upper grate 70 whose lower contracted end constitutes a spout which delivers them to the right side of the machine above the running board 8. Although I have not so shown it, provision may be made for mounting sacks or bags beneath the several spouts so that the graded potatoes may be put into their proper receptacles, and the operator from time to time will set them off onto the ground as the machine progresses. I have given the operation of this machine and the uses of its various instrumentalities as the

description of their construction and location occurs in the above specification, but it may be well to call attention to the fact that the potatoes gathered are first carried upward and dropped onto the vibrating carrier and move under the fingers 37 if they are employed in conjunction therewith, and by this carrier or its fingers or both, the tubers are caused to move through the various fingers and are automatically detached from the tops whereas the tops are dropped at the rear end of the machine with the exception of such small particles as yet adhere. Thus the potatoes are carried forward and elevated, and by the spout 49 are delivered to the rollers where the remaining particles are drawn from them before they are graded. The grader sorts out the small potatoes from the large ones and delivers the different sizes at different points for sacking if desired, and through all this course much agitation has been involved so that the dirt on the potatoes is removed, even though they may have been gathered in a quite wet and muddy condition.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

1. The combination with a carrier including rollers and an endless slatted belt whose upper and lower stretches move in opposite directions near each other; of a grid-like structure including longitudinal fingers fixedly supported by the roller shafts and disposed between said stretches of the belt whereby material carried by the upper

stretch thereof may hang through the grid to be struck by the slats in the lower stretch.

2. The combination with a frame and rollers journaled across the ends of the frame, one of them being in sections; of fingers 50 mounted at one end on the roller shaft between its sections and their bodies extending thence to the other roller, and an endless slatted belt moving around the rollers and fingers. 55

3. The combination with a frame, means for vibrating it, and rollers journaled across the ends of the frame, one of them being in sections; of fingers having eyes at one end mounted on the roller shaft between its sections and their bodies extending thence to the other roller, and an endless slatted belt moving around the rollers and fingers. 60

4. The herein described carrier comprising a frame, a roller journaled in one end 65 thereof, a sectional roller journaled in the other end thereof, chains connecting said rollers, cross strips connecting said chains, and a series of fingers having eyes at one end mounted on the shaft between the sections of said sectional roller and their other ends overlying the other roller. 70

5. In a carrier for the purpose described, the combination with a frame, parallel rollers therein, one roller being in sections, a 75 series of fingers having eyes disposed on the shaft between said sections and their other ends overlying the other roller, and the carrier proper consisting of two chains connecting said rollers and cross strips connecting 80 the chains and traveling over said fingers; of a cross head, and a second series of fingers carried thereby and overlying said strips.

In testimony whereof I affix my signature in presence of two witnesses.

HENRY RINK.
